(57) **CLAIM**

The ornamental design for a note pad for organizer clip, as shown and described.

DESCRIPTION

FIG. 1 is a perspective view of a note pad showing our new design in accordance with the invention;

FIG. 2 is a front elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines showing environment in drawings are for information purposes only and form no part of the claimed design. The broken lines showing the edges of the sheets of the note pad indicate that no particular number of sheets is claimed.
